W. A. LA MOTTE.

ELECTRIC HEATER.

APPLICATION FILED NOV. 14, 1916.

1,242,209.

Patented Oct. 9, 1917.

INVENTOR
Wilbur A. La Motte,
BY
Fried C. Fischer
ATTORNEY

UNITED STATES PATENT OFFICE.

WILBUR A. LA MOTTE, OF ELIZABETH, NEW JERSEY.

ELECTRIC HEATER.

1,242,209.

Specification of Letters Patent.

Patented Oct. 9, 1917.

Application filed November 14, 1916. Serial No. 131,224.

To all whom it may concern:

Be it known that I, WILBUR A. LA MOTTE, a citizen of the United States, residing in the city of Elizabeth, in the county of Union 5 and State of New Jersey, have invented certain new and useful Improvements in Electric Heaters, of which the following is a full, clear, and exact description, such as will enable others skilled in the art to which 10 it pertains, to make, construct, and use the same, reference being had to the accompanying drawings and to numerals of reference marked thereon, forming a part of this specification.

15 This invention relates to electric fluid heaters, and has for its object the provision of a device of this character, in which the fluid may be heated to any desired temperature in a simple and efficient manner.

20 More especially, my invention relates to what are known as electrolytic-heaters, in which the fluid is heated directly by the current, that is, the fluid forms a part of the electric current.

25 The present invention consists primarily of a novel device of the character described, comprising a liquid receptacle provided with a bearing at one end, and further provided with an integral seat in the bottom thereof, 30 a support provided with recesses secured upon said seat, electrodes each having one end secured in said bearing, and the other seated in the recesses of said support, and electrical connections for said electrodes, and 35 furthermore, this invention consists in the various novel arrangements and combination of parts, all of which will be described in detail in the following specification, and then finally embodied in the clauses of the 40 claims.

In the accompanying drawings, in which I have shown a preferred form of my invention,

45 Figure 1 represents a sectional plan view of a receptacle made in accordance with my invention, taken on lines $x-x$ of Fig. 2, the cover being removed, and

Fig. 2 represents a side elevation of the same.

50 Similar characters of reference refer to like parts throughout the specification and drawings.

In the drawings, 1 represents a receptacle or container, preferably made of cast aluminum, although porcelain or any other 55 suitable non-corrosive material may be em-

ployed, which may be of any shape or size, according to the purpose to which it is adapted. It may be ornamented in any suitable or desirable manner in case it is intended for use on the table in the heating of liquids in the preparation of foods or the sterilizing of instruments. A cover 2 of any convenient form and provided with a handle 3, preferably of fiber, is removably mounted upon said receptacle or container 1. Similar handles are secured to the sides of the container and the bottom thereof is preferably provided with a plurality of fiber feet 4.

70 Within the container or receptacle 1 are arranged the electrodes 5—5, between which the fluid is to be heated. These electrodes are preferably similar in size and shape, and made of some suitable non-corrodible conductor, as graphite or the like. As shown, said electrodes are supported on one end in recesses formed in a suitable porcelain or other non-conducting bracket 6, which is secured by means of screws 7 or the like, 75 upon an integral seat 8 formed on the inside of the receptacle or container 1. The other ends of the said electrodes are preferably cylindrical in form, said cylindrical ends fitting into metallic sockets 9 from which 80 extend the electrical connections in the form of metallic terminals 10, which may be secured thereto in any convenient or desired manner.

85 Surrounding and inclosing said metallic 90 sockets 9, are porcelain or other non-conducting bushings 11, which are received into suitable recesses 12 formed in an integral bearing 13 extending into and projecting outward from the receptacle or container 1 95 near the bottom and one end thereof, as clearly indicated in the drawings.

90 Suitable apertures are formed in said bearing 13 to receive bushings 14, through which the terminals 10 pass. The bushings 100 14 also form a water-tight joint.

95 The manner of supporting said electrodes may, however, be varied in any manner which suggests itself to persons skilled in the art, to meet varying requirements.

100 In the passage of the current through the resistance offered by the water, heat is generated and the liquid contained within the receptacle heated very rapidly. When there is no liquid within the receptacle, there is 110 of course, no action and no burning out of the parts.

Within the receptacle or container 1 are provided a number of integral supports 15, preferably projecting above the electrodes and upon which may be secured by means of 5 screws, or removably mounted, an instrument tray 16 or the like, said instrument tray in its preferred form, consisting of a sheet of perforated aluminium or other suitable non-corrosive material.

10 Experience has demonstrated that the organization above described is a highly efficient one, and while the device described is the preferred embodiment of my invention, I do not wish to be limited to the exact 15 details of construction, combination and arrangement herein shown and described, as obvious modifications thereof, not involving the exercise of invention, may be made by any one skilled in the art, and such departures from what is herein shown and described, I consider within the scope and 20 terms of my claims.

Having thus described my invention, what I claim as new and desire to secure by Letters Patent is:—

1. An electric heater comprising a liquid receptacle, provided with a bearing at one end, and further provided with an integral seat in the bottom thereof, a support provided with recesses secured upon said seat, electrodes each having one end secured in 30 said bearing and the other seated in the recesses of said support and electrical connections for said electrodes.

2. An electric heater comprising a receptacle having a bearing at one end, insulating bushings located in said bearing, metallic bushings secured within said insulating bushings, and metallic terminal pins extending from said bushings through the insulating bushings, means located in said bearing surrounding said terminal pins for maintaining a water-tight joint, a support provided with recesses located within the receptacle, electrodes each having a reduced 45 end, said end being secured in said metallic bushings and the other ends of said electrodes seated in the recesses of said support.

3. An electric heater comprising a liquid 50 receptacle, provided with a bearing at one end, and further provided with an integral seat in the bottom thereof, a support provided with recesses secured upon said seat, electrodes each having one end secured in 55 said bearing and the other seated in the recesses of said support, and electrical connections for said electrodes and a perforated plate removably mounted in said receptacle in close proximity to and above said electrodes.

This specification signed and witnessed this eleventh day of November, 1916.

WILBUR A. LA MOTTE.
